MUCKING MACHINE

William A. Whitmire, Albany, Calif.

Application February 25, 1936, Serial No. 65,667

3 Claims. (Cl. 214—134)

This invention, a mucking machine, is particularly adapted to mucking operations in confined areas, such as small tunnels, drifts and excavations, due to the extremely compact arrangement 5 and method of operation. However, this machine can be built in any desired size for operation under any conditions, although its prime advantage lies in its compactness for operation in restricted or confined locations.

10 This invention is an improvement over my co-pending application, Serial Number 53,466 filed December 9, 1935 and which application is directed to the specific combination illustrated and described, while this application is particularly 15 directed to the particular type and arrangement of dipper and dipper sticks, together with conveyor arrangement and the new results obtained thereby.

To produce a unit which can be conveniently 20 and successfully operated in very narrow tunnels or drifts, all transverse space must be rigidly conserved to provide a space for the operator at a point where the operator can properly guide the dipper and watch the results of his operations.

25 It is for this reason that this improvement is advanced, since it conserves space and provides a location at the operating end of the machine for the operator, and provides room under the conveyor for all of the operating mechanism, while also leveling out the conveyor which carries the muck away as dumped from the dipper.

The objects of the invention are as follows:

First; to provide a dipper and dipper-stick arrangement which positively inverts the dipper during raising thereof.

Second; to provide a dipper-stick arrangement which is adjustable at will to effect predetermined degrees of inversion of the dipper for a predetermined angular lift, whereby an inversion of greater than ninety degrees may be obtained with an angular lift of less than ninety degrees.

Third; to provide an assemblage of dipper sticks as outlined, which assemblage is of minimum transverse cross-section for conservation of space for an operator's location within complete observation of all operations of the dipper.

Fourth; to provide an automatic latching device for the dipper cover, to automatically release the cover at the terminal of lift, and automatically lock the cover as the dipper is lowered.

Fifth; to elevate the tail pulley of the conveyor to the highest level at which the dipper can dump directly thereon, so as to dispense with 55 a hopper or a chute, reduce the inclination of the

conveyor, prevent accumulation of muck, and provide ample space under the conveyor for all mechanism and driving devices.

Other objects and advantages of the invention will become apparent as the following description 5 is read on the drawings forming a part of this specification, in which similar reference characters are used to designate similar parts throughout the several views, of which:

Fig. 1 is a sectional plan view of the invention 10 taken on line 1—1 of Fig. 2, the rear portion of the machine being omitted.

Fig. 2 is a side elevation of the invention.

Fig. 3 is an enlarged plan view of the dipper and dipper-stick arrangement.

Fig. 4 is a side elevation of Fig. 3.

Fig. 5 is a section taken on line 5—5 of Fig. 4.

Fig. 6 is a front view of the dipper.

Fig. 7 is a fragmentary side view of the dipper showing the automatic dipper-cover latch.

The dipper indicated in its entirety as 10 is open at the front 11, and has a cover 12 which is hinged near the forward end of the top as shown at 13, whereby, as the dipper is inverted, the cover will swing open, and close again when lowered, through gravitational influence.

The dipper also has side walls 14 and 15, back wall 16, bottom 17 terminating at its forward end in rakes or teeth 18, and also has a top cross-strut 19 to tie the front end of the sides together 20 and form a rigid structure.

A bail 20 is pivoted to the respective side walls 14 and 15 as shown at 21, and a lifting cable 22 is attached to the bail 20 by any known means.

The dipper stick is of a new and unusual arrangement, consisting of two pairs of links arranged in crossed and intervening relation, the sticks or links 23 and 24 of one pair being in angular or crossing relation to the other pair 25 and 26, which pair 25—26 is located between the 35 links 23 and 24.

All four links 23 to 26 have their respective ends pivotally attached to the rear wall of the dipper through brackets 27 and 28, as shown at 29 and 30; and to the crowd head 31, as shown at 32 and 33, the vertical distance between pivots 29 and 30 being fixed, while the vertical distance between pivots 32 and 33 is made adjustable by provision of spaced-apart holes 34, 35 and 36, whereby the relative inversion of the dipper may be 45 varied at will. The greater the distance between these pivot points, the greater the angle of inversion or tipping as related to the angular lift of the dipper stick.

When the pivot spacing at both ends of the 55

links is equal, the inversion angle is double that of the angular lift, therefore an angular lift of 70° will rotate the dipper through 140°. With increased spacing at the crowd end, the inversion of the dipper would be correspondingly increased for the same angular lift.

The dipper is shown dotted in three additional positions in Fig. 2, and as will be noted, as the dipper is raised from position 31 to position 38, 10 the dipper is tipped back, causing the teeth 18 to advance upwardly into the material instead of drag, as is usually the case, and further, causes the muck to settle back into the dipper, permitting the dipper to be completely filled, 15 which does not occur with the usual type of dipper arrangement.

As the dipper reaches the position 40, it has been inverted, or rotated through an angle of about 135°. However, the degree of inversion 20 may be varied by adjusting the pivots 32—33. If brought closer together, the degree of inversion will be less, while if the pivots are adjusted farther apart, the inversion will be increased.

The purpose of this adjustment is two-fold. 25 First, the degree of inversion may be adjusted according to the angle of repose of the muck; and second, where there is lack of head room, as in low tunnels, the entire structure for dumping may be built lower, either by adjustment, of 30 by structural arrangement, and the dipper can be made to tip through 135° for a 45° lift of the dipper stick. Thus the dipper could be caused to dump in the position shown at 41.

The crowd head 31 is fixed on, or integral with, 35 the head end of the crowd 42, which slidably operates between the ways 43, and any suitable operating means, such as compressed air, steam, or, as shown, a motor 44, driving through suitable reduction gearing 45, may be used to force 40 the crowd and dipper, and retract the same, the crowd having teeth 46 with which the gearing cooperates.

The ways 43 are mounted in a frame 47 which is supported on a carriage frame 48 to which it 45 is pivotally secured as at 49; this carriage frame being mounted on wheels 50.

A superstructure 51 of suitable form and strength supports the conveyor 52 and its driving means, such as a motor 53, as also the winch 50 or tugger 54 for the dipper cable 22. The tugger driving means 55 may be located as shown, or may be located under the conveyor, if desired.

The latching means for the cover 12 consists of a latch 56 which is intermediately pivoted at 55 57 to the side wall 14 or 15, and counterweighted as indicated at 58, the latch engaging over the rear edge of the cover 12 or over an integral, transversely extending lug 59, and having an engaging face 60 and a release head 61 for automatic release of the latch.

The release head 61 cooperates with the tail apron 62, or with the superstructure 51, at the

terminal of lift of the dipper, releasing the cover 12 and depositing the muck on the conveyor 52, the muck being thereby conveyed to a dump car (not shown) back of the mucking machine.

As will be noted, the specific, transversely compact arrangement of frame or superstructure, conveyor, and dipper stick, provides ample space at one side for an operator's seat 63 and necessary control levers 64, in a position for accurate control of the operation of the dipper.

This arrangement of dipper stick also provides extreme rigidity for positive and direct rectilinear action of the dipper.

It will be understood that variations in construction and arrangement of parts, which variations are consistent with the appended claims, may be resorted to without detracting from the spirit or scope of the invention, or sacrificing any of the advantages thereof.

I claim:

1. In a mucking machine, a dipper and rectilinear crowding means therefor, and a multiple element dipper stick pivotally cooperating between said dipper and said crowding means, predetermined elements acting in opposition to the other elements causing inversion of the dipper as the dipper is raised, a hinged cover for said dipper and automatic latching and unlatching means therefor operating gravitationally for latching and by cooperation with a conveyor frame for unlatching only when the dipper is in inverted position, and a conveyor receiving material from said dipper directly without intervening hopper.

2. In a mucking machine, a dipper having a back provided with an upper and a lower pivot bearing, a rectilinearly acting crowd having a head provided with an upper and a series of lower spaced apart pivot bearings, and a dipper stick consisting of links connecting said bearings in crossing relation, said series of lower pivot bearings permitting adjustment of the vertical spacing at one end of the links to vary the angle of inversion of the dipper during raising relative to the instant median angle of the links.

3. In a mucking machine, a frame, a rectilinearly acting crowd having a head provided with a plurality of spaced apart horizontal pivot apertures in vertical alignment, a dipper having a back provided with a plurality of spaced apart horizontal pivot apertures in vertical alignment, links pivotally connecting through said apertures between said head and said dipper in crossing relation, a hinged cover for said dipper opened and closed during operation through gravitational influence, and a latch latching said cover upon closing and released through cooperation with said frame during the final inverting movement of said dipper as the dipper is raised to dumping position, and means for raising said dipper.

WILLIAM A. WHITMIRE.
